[57] CLAIM

The ornamental design for a softball shoe sole, as shown and described.

DESCRIPTION

FIG. 1 is an outside elevational view of a softball shoe sole showing my new design;

FIG. 2 is a top plan view thereof;

FIG. 3 is an enlarged front elevational view thereof;

FIG. 4 is an enlarged rear elevational view thereof;

FIG. 5 is an enlarged inside elevational view thereof;

FIG. 6 is an enlarged bottom plan view thereof;

FIG. 7 is a fragmentary sectional elevational view taken along the line 7—7 of FIG. 6;

FIG. 8 is a fragmentary sectional elevational view taken at 90° to FIG. 7 and showing the inner side of the cleat in FIG. 7;

FIG. 9 is a fragmentary sectional elevational view taken along the line 9—9 of FIG. 6;

FIG. 10 is a fragmentary sectional elevational view taken along the line 10—10 of FIG. 6;

FIG. 11 is a fragmentary sectional elevational view taken along the line 11—11 of FIG. 6;

FIG. 12 is a fragmentary sectional elevational view taken at 90° to FIG. 11 and showing the right side of the cleat in FIG. 11;

FIG. 13 is a fragmentary sectional elevational view showing the outer side of the cleat in FIG. 11;

FIG. 14 is a fragmentary sectional elevational view taken along the line 14—14 of FIG. 5; and

FIG. 15 is a fragmentary sectional elevational view taken at 90° to FIG. 14, and showing the right end of the cleat in FIG. 14.

The broken line showing of a softball shoe upper in FIG. 1 is for illustrative purposes only and forms no part of the claimed design.
